UNITED STATES PATENT OFFICE.

JOHN J. VERWYS, OF SPARTA, MICHIGAN, ASSIGNOR TO THE WELCH MFG. CO., OF GRAND RAPIDS, MICHIGAN.

REVOLVING-RACK SHOWCASE.

Application filed June 15, 1922. Serial No. 568,437.

To all whom it may concern:

Be it known that I, JOHN J. VERWYS, a citizen of the United States, residing at Sparta, county of Kent, State of Michigan, have invented certain new and useful Improvements in Revolving-Rack Showcases, of which the following is a specification.

This invention relates to improvements in revolving rack show cases. It relates more particularly to that style of show case which appears in Letters Patent No. 1,023,186, issued April 16, 1912.

The object of this invention is to provide improved ways for the carriage and to provide improved interlocking means which prevents a rotation of the rack within the show case and until the rack is in forward position and locks the carriage in front position until the rack is turned to position.

Objects pertaining to details and economies of construction and operation will definitely appear from the detailed description to follow.

I accomplish the objects of the invention by the devices and means described in the following specification. The invention is clearly defined and pointed out in the claims.

A structure embodying the features of the invention is clearly illustrated in the accompanying drawings forming a part of this application, in which:

Fig. I is a detail plan view of the carriage base bar of the revolving rack and the ways for the carriage, the decking over the carriage being removed and parts of the base bar being broken away to show details of construction, the forward position of the lock parts being indicated by dotted lines.

Fig. II is an enlarged detail transverse sectional elevation view, taken on line 2—2 of Fig. I, the carriage appearing in full lines.

Fig. III is an enlarged detail plan view, portions of the latch 30 being broken away, showing the front position of the devices in full lines ready to lock the carriage on turning the rack, the preceding relation in dotted lines and the lock disk and roller being also shown dotted.

Fig. IV is an enlarged transverse detail sectional elevation view taken on irregular line 4—4 of Figs. I and III, parts being in full line.

In the drawings the sectional views are

taken looking in the direction of the little arrows at the ends of the section lines and similar numerals of reference refer to similar parts throughout the several views.

Considering the numbered parts of the drawings by their numbers, 1 is the floor of the case. 2, 2 are the transverse cross beams beneath the floor which support the carriage ways 4 for the transversely traveling carriage. These are connected together by end bars, 3, 3 (see Figs. I and II). The carriage ways 4 supported by the said cross beams 2, 2 are provided with ball races 5, 5 on their inclined faces to receive the bearing balls 11. 6 is the front supporting cross bar connecting the side beams and rails together. 7 is the carriage, having brackets 8, 8 at each corner, in which are adjustably secured the longitudinal side rails 9 which are provided with ball races 10 disposed in position with obliquely under inclined faces to cooperate with the ball races 5 of the guide ways.

The faces of these guide rails and side rails are slightly inclined so that the bearing balls 11 rest upon a slight projecting ledge and also engage under a projecting or over hanging ledge on the carriage side rails. This insures their smooth and even action without shearing strain upon the balls. The shearing action by this expedient is almost completely avoided and the balls run much more smoothly than between bars and rails with races in their vertical faces.

12 is the upright column of the revolving rack supported on the ball bearing turntable 13. The base bar 14 carries the usual upright columns 15, 15 at each end which support the display rack at the upper end, these details not being shown, as my invention does not pertain thereto.

16 is the decking over the carriage and ways and is suitably slotted for the passage of the upright column 12. 17, 17 are yielding spring latches on the ends of the carriage 7 adapted to snap over and engage the catch roller 18, 18 at each end. 20, 20 are stops which limit the motion of the carriage and locate the same in correct operative position, toward the front or in the right relation to the back wall within the case.

A horizontal lock disk 21 is supported in the said carriage and is secured by suitable means to the lower portion of the column 110

12 and is notched at 22, 22 on opposite sides to receive suitable retaining or detent rollers 25. Levers 23, 23 are fulcrumed at 24, 24 toward the rear of said carriage, and 5 project forwardly, each carrying one of the retaining or detent rollers 25, 25 to cooperate with the said notches 22, 22. The forward ends of these levers are connected by coil tension spring 26 which puts tension 10 upon the same and causes them to engage the horizontal disk 21 yeldingly, causing a slight braking action upon the revolving rack.

A laterally projecting locking latch 27 is 15 pivoted at 27' towards the front end of one of the levers 23. This is notched at 27'' and cooperates with the stop 28 securely bolted by the bolt or set screw 28' to the side rail 9 of the carriage—see Fig. IV. When the 20 carriage is within the case it is in the position shown by full lines in Fig. I and lever 23 with detent roller 25 is locked against disk 21 preventing its rotation. The stop pin 29—see Figs. III and IV—limits the 25 movement of the said stop latch 27 which swings between the stop 28 and the forward end of the lever 23, positively retaining and locking the same in position as pointed out, until moved to the front of the case. Means 30 are provided to release this lock in front position. A lever 30, which has an offset portion 30', is also supported on the pivot 27' and is pinned by pin 30'', to said latch 27—see Figs. I, III and IV, so that the latch 35 and lever swing together. Lever 30 is pulled forward and held in forward position by the tension spring 31 which connects at the perforation 32 to the said lever and by screw 33 to the front corner of the carriage 7. 40 Lever 30 is also a locking bolt.

The end of the lever 30 projects beyond the side edge of the carriage 7 and is disposed to cooperate with the stop 34 which is held by set screw 35 to the guide rail 4. 45 This stop block 34 has a stop portion 34' facing towards the front of the show case, and an engaging stop portion 36 facing toward the interior of the said show case. These stops are in slightly offset relation, as 50 appears in Figs. I and III. The end of lever 30 passes the inner stop on the outer travel of the carriage and strikes stop 36. The stop is so located that the movement of the carriage to the end of its ways swings 55 lever 30 and with it latch 27 out of engagement with stop 28. This permits lever 23 to swing in turning disk 21 and the end of lever 30 will be shot like a bolt in front of stop 34'.

60 Anti-friction roller 38 facilitates the movement of the said lever 30 into its stop position.

The relation of the interlock will be understood from an examination of Figs. I and III. When the carriage is in the "in"

position indicated in Fig. I the latch 27 engages the stop pin 29 and holds the lever 23 firmly in position with the engaging roller 25 in the notch 22, thus preventing the rotation of the carriage, and the rack is held 70 in this locked position in relation to the carriage until the carriage is moved to the front of the case. When the carriage is moved to the front of the case, the outer end of the lever 30 finally contacts with the stop portion 36 of the stop 34 and yields until the same is swung substantially to the right angle position indicated by the dotted lines of Fig. I, when the forward spring catch 17 engages the forward roller 18 and the stop 20 80 limits the further movement of the carriage. This swings the latch 27 which is pinned to lever 30 out of engagement with the stop 28 and it is then possible to revolve the rack of the show case, which lifts the roller 25, which is now free to yield, and swings the lever 23 to one side. This in turn forces the end of the latch lever 30 past the roller 38 so that it will engage with the stop 34'. Then, because the latch lever 30 is thus engaged between the stops like a bolt, the carriage cannot be pushed in. The notched portion 27'' then engages at one side of the stop 28 and because the end of the latch lever 30 is engaged by the stop 34 the carriage is 90 locked in position and cannot be moved back into the case until the revolving rack has been turned to the correct position cross way of the carriage to permit the same to be engaged by roller 25 and the latch lever withdrawn. When the rack is thus swung to the right position it is possible to move the carriage back into the case, automatically locking the rack against rotation at all times except when it is in the front position where it 100 is free to revolve and display the goods thereon and at the same time lock the carriage in the front or display position.

I have described my improvements in the form preferred by me. The same can be varied as to details. However I desire to claim the invention in the specific form and also broadly, as pointed out in the appended claims.

Having thus described my invention what 115 I claim as new and desire to secure by Letters Patent is:

1. In a revolving rack show case, the combination of a suitable carriage, a revolving rack on a suitable revolving column on said carriage, side rails for said carriage, a disk carried by the said column with notches on opposite sides thereof, levers pivoted to the said carriage and carrying detent rollers 120 adapted to engage the notches on said disk, a spring for drawing the said levers together to engage the said horizontal disk, a pivoted locking latch pivoted to one of said levers, a stop on the side of said carriage cooperating with the end of said latch 125 130

- to lock said lever against movement, an angularly disposed lever fulcrumed on the pivot of said latch and pinned thereto, a spring for drawing the same yieldingly forward, a double stop on the side rail with one stop portion to act upon said latch and swing it out of engagement and the lever to the right angle position when the carriage is pulled to the front position and 5 the other stop to engage the said pivoted lever when the yielding lock lever is moved outward by the turning of the rack to lock the carriage in front position until the rack is turned crosswise, coacting as specified.
- 10 2. In a revolving rack show case, the combination of a suitable carriage, a revolving rack on a suitable revolving column on said carriage, side rails for said carriage, a disk carried by the said column with notches on 20 opposite sides thereof, a lever pivoted to the said carriage and carrying a detent roller adapted to engage the notches on said disk, a spring acting on the said lever to engage the said horizontal disk, a pivoted locking latch pivoted to said lever, a stop on the side of said carriage cooperating with the end of said latch to lock said lever against movement, an angularly disposed lever fulcrumed on the pivot of said latch 30 and pinned thereto, a spring for drawing the same yieldingly forward, a double stop on the side rail with one stop portion to act upon said latch and swing it out of engagement and the lever to the right angle position when the carriage is pulled to the front position and the other stop to engage the said pivoted lever when the yielding lock lever is moved outward by the turning of the rack to lock the carriage in front position until the rack is turned crosswise, coacting as specified.
- 35 3. In a revolving rack show case, the combination of a suitable carriage, a revolving rack on a suitable revolving column on said carriage, side rails for said carriage, a disk carried by the said column with notches on opposite sides thereof, levers pivoted to the said carriage and carrying detent rollers adapted to engage the notches on said disk, a spring for drawing the said levers together to engage the said horizontal disk, a pivoted locking latch pivoted to one of said levers, a stop on the side of said carriage cooperating with the end of said latch to lock said 40 lever against movement, an angularly disposed lever fulcrumed on the pivot of said latch and pinned thereto, a spring for drawing the same yieldingly forward, a stop on the side rail positioned to act upon said latch and swing it out of engagement, and a carriage locking means disposed to be actuated by the said latch when it is swung outward by the rotation of the carriage to retain the said carriage in front position until the rack is turned crosswise and the latch withdrawn, coacting as specified. 55
4. In a revolving rack show case, the combination of a suitable carriage, a revolving rack, a suitable revolving column on said carriage, a disk carried by said column with a suitable notch in the periphery thereof, a lever suitably pivoted with a detent roller disposed to engage said notch and lock the rack in crosswise position, a spring holding said lever yieldingly into engagement with the disk, a locking latch carried by the said lever, a stop on the side of the carriage cooperating with the end of said latch to lock said lever against movement, a stop means for swinging the lock out of engagement 60 when the carriage is in the forward position, a double stop on the side rail with one portion to act upon said lock and release the same when the carriage is pulled to the front position and the second stop to engage the said lock when the yielding lever is moved outward by the rotation of the carriage to lock the same in its front position until the rack is turned crosswise, as specified. 65
5. In a revolving rack show case, the combination of a suitable carriage with straight side rails having obliquely inclined under faces with straight ball races therein whereby the upper part of said ball race overhangs the balls, straight guideways supported in said case parallel to said side rails with obliquely inclined faces corresponding thereto with an under projecting portion beneath the balls opposed to the overhung rails, antifriction balls within the said races and between the overhung and under projecting parts, and detents for said carriage, coacting as specified. 70
- In witness whereof, I have hereunto set my hand and seal. 75
